UNITED STATES PATENT OFFICE.

ALPHIEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

DRAIN BOARD FOR WRINGERS.

Application filed April 10, 1924. Serial No. 705,559.

This invention has reference to certain new and useful improvements in drain-boards for wringers, being adaptable to swinging as well as the stationary type.

The invention has for its principal object to provide a drain-board, comprising a single unit fulcrumed mediate its ends to the wringer frame in the same vertical center line with the axes of the wringer rolls and having a substantially flat surface for the greater portion of its length terminating at its opposite ends in downwardly inclined or tapered surfaces, each being adapted to assume an approximately horizontal plane in relation to the vertical center line of the wringer rolls when the board is tilted in either direction; such surfaces at the ends of the board providing a non-restricted discharge surface or shelf at the discharge side of the wringer rolls.

The invention has for a further object to provide a drain-board pivoted mediate its ends and with a substantially flat surface for the greater portion of its length terminating at its opposite ends in downwardly inclined or tapered ends with abrupt dripping ends and with means therebeneath for affecting a rapid drip and to retard the flow of water back underneath the board.

A further object of the invention is to provide a drain-board for wringers pivoted mediate its ends and in the provision of locking means disposed above the fulcrum point of the board and on each side thereof to effect a positive lock when the board is tilted in either direction.

That the invention may be more fully understood, reference is had to the accompanying drawings forming a part of the description, illustrating a preferred embodiment of the invention, in which:

Figure 1 is a side elevation of a wringer having a drain-board embodying my invention;

Figure 2 is an end view of Figure 1, and

Figure 3 is a vertical cross-section through the wringer frame, rolls and drain-board, dotted lines showing the reverse position of the board.

Like characters of reference denote corresponding parts throughout the figures.

I am not here concerned whether the wringer is of the stationary or swinging type, although the drawings disclose a

swinging wringer, dotted lines both showing the standard providing a mounting for the wringer and the washing machine frame.

1 designates a wringer frame provided preferably, with a pair of superimposed gearless, resiliently mounted wringer rolls 2 and 3. Below said rolls and between the side supports 4 of said frame is pivotally mounted a drain-board 5, the fulcrum for the board being mediate its ends, as at 6, to the side supports 4 and preferably in a vertical plane intersecting the axes of the two rolls 2 and 3, as shown in Figure 3. The board 5 comprises preferably, a single unit and being pivoted mediate its ends is adapted to be tilted, alternatively in opposite directions to provide a drain on either side of and from the wringer rolls, as shown in full and dotted lines in Figure 3. I provide means to lock the drain-board in its two different tilted positions, and such means comprises the pivoted latch members 7 provided with shoulders 8 adapted to overlie and engage the upper edge of a side rail of said board. These members 7 are preferably pivoted above the fulcrum 6 of the board and to each side thereof and are so suspended by their pivots that they tend to swing inwardly toward the side rail of the board, one being held away therefrom, as shown in Figure 1 by the upwardly tilted end of the board while the other swings toward the board and overlies the downwardly tilted end of the board to lock the same in such tilted position. By releasing the locking member and reversing the position of the board the other member 7 will act to lock the board in such position.

The board 5, as shown in Figure 3, for the greater portion of its length is provided with the substantially flat central surface 9, terminating at its opposite ends in the downwardly and forwardly inclined or tapered surfaces 10, which alternatively, as the tilted position of the board is changed presents an approximately horizontal plane in relation to the vertical center line of the wringer rolls, such surfaces providing non-restricted discharge surfaces or shelves at the discharge side of the wringer. This is well brought out by the full lines in Figure 3, where the arrows to the right illustrate the movement of materials passed through the rolls and how such a surface or shelf will

prevent such materials turning back into a pocket beneath the rolls. Such a condition would arise with a single unit board pivoted mediate its ends, if not provided with sloping surface ends, and is prevented by the sloping ends of the board which present the approximately horizontal surfaces or shelves over which the materials leaving the rolls will pass with a free movement and without danger of being forced back into a pocket underneath the rolls.

The ends of the board are provided with rather sharp dripping edges 11 and beneath the board adjacent the ends are provided the abrupt angular surfaces 12 which will retard the back flow of water beneath the board, and effect a rapid drip of water therefrom, as illustrated in a diagrammatic way at the left of Figure 3.

20. What I claim is:—

1. In combination with a wringer frame, a drain board pivoted at a fixed point mediate its ends below and in vertical alinement with the wringer rolls, and extending for some distance on each side of the rolls, said board having a substantially flat central surface and having the ends thereof terminating in downwardly inclined surfaces, said downwardly inclined surfaces being of substantial length and each adapted upon tilting of the board to assume an approximately horizontal position so as to provide for free movement for a distance in a horizontal plane of the articles being wrung prior to such articles engaging with the ends of the board.

2. In combination with a wringer frame, a drain board pivoted at a fixed point mediate its ends below and in vertical alinement with the wringer rolls, and extending for some distance on each side of the rolls, and a pair of pivoted locking members for holding the board in different tilted positions, each locking member having a downwardly facing shouldered part which receives the

side of the board and rests on the top face thereof.

3. In combination with a wringer frame, a drain board pivoted at a fixed point mediate its ends below and in vertical alinement with the wringer rolls, and extending for some distance on each side of the rolls, and a pair of pivoted locking members for holding the board in different tilted positions, each locking member having a right angular part which when in operative position extends along the side of the board and over the top thereof and engages the top face of the board side.

4. In a device of the character described, in combination with the wringer frame and rotatable wringer rolls, of a drain-board comprising a single unit pivoted mediate its ends below and in the same vertical center line of the rolls and extending some distance on each side thereof, said board having a substantially flat surface for the greater portion of its length terminating at its ends in downwardly inclined surfaces, each adapted to alternatively assume an approximately horizontal position when the board is tilted, to provide a non-restricted discharge surface at the discharge side of the wringer rolls, the ends of the board presenting sharp dripping edges and the board beneath and adjacent said ends provided with angular dripping surfaces.

5. A drain-board for wringers, comprising a single unit arranged to be pivotally supported at a point mediate its ends, and having a substantially flat surface for the greater portion of its length terminating in downwardly and forwardly inclined surfaces at its opposite ends, the ends of said inclined surfaces presenting sharp dripping edges and provided with angular dripping surfaces therebeneath.

In witness whereof, I have hereunto affixed my hand this 8th day of April, 1924.

ALPHEUS W. ALTORFER.
